UNITED STATES PATENT OFFICE.

LOUGH P. SIGLER, OF DALLAS, TEXAS.

STAFF AND JEWEL MOUNTING FOR WATCHES.

Application filed May 31, 1927. Serial No. 195,325.

This invention relates to new and useful improvements in staff and jewel mountings for watches.

The object of the invention is to provide a mounting for the balance staff of a watch which will be yieldable so that the jewels forming the bearings will not be cracked or broken from sudden shocks or jars.

A further object of the invention is to provide a mounting for each end of the balance staff comprising bearing members arranged to undergo, relatively of the balance staff, both a longitudinal and a transverse or lateral movement, thus yielding in all directions.

A still further object of the invention is to provide a mounting for each end of a balance staff including a pair of jewels, each mounted in individual members and said members being so arranged as to undergo longitudinal and lateral movements under the influence of a single spring element, thus obviating the necessity of providing a spring element for each individual jewel mounting member.

Another object of the invention is to provide a jewel mounting comprising a pair of resiliently sustained inter-meshing jewel mounting members so arranged as to maintain their intermeshed relation and positive contact while undergoing the various movements.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a vertical sectional view of a portion of a watch movement showing the balance staff and jewel mountings constructed in accordance with my invention,

Fig. 2 is a plan view of one of the mountings,

Fig. 3 is an underside view of the cap jewel mounting member,

Fig. 4 is a plan view of the mounting member for the perforated jewel, and

Fig. 5 is a sectional detail showing portions of the mounting members in displaced relation.

In the drawings, which are, of necessity, shown upon a greatly enlarged scale, the numeral 10 designates the lower plate of the

watch movement and 11 the upper bracket for supporting the upper end of the balance staff 12, the plate and bracket being provided with circular recesses 13 for the reception of the jewel boxes 14 in which the mounting members are confined.

As the mechanism in each jewel box is substantially the same a description of one will suffice for both, and the box which is inserted in the recess 13 of the bracket 11 will be used. The box has a cylindrical body with one end open and the other end closed by a circular plate 15 overhanging the body and provided with a central or axial opening 16. The opening 16 is considerably larger in diameter than the pivot 17 of the staff 12. The plate 15 has a collar 18 surrounding the opening 16 and the staff 12 has a shoulder 19 overhanging the pivot 17. This shoulder is adapted to engage the collar and limit the longitudinal thrust of the staff.

Within the box is arranged an annular jewel-mounting member 20 in the center of which the usual perforated jewel 22 is suitably secured. A second annular jewel-mounting member 23 is also disposed in the box in contact with the member 20 and has mounted therein the usual cap jewel 24. The pivot 17 has a reduced spindle 25 extending through the perforated jewel 22 and bearing against the jewel 24 in the usual manner.

A spring tension member or disk 26 is fastened on the bracket 11 by a pair of screws 27 and is provided with a central opening 28. Spring fingers 29 are bent down from the disk on diametrically opposite sides so as to bear on top of the cap member 23 on each side of its central opening. The box may be cut away at 14' to permit the fingers to freely flex. The disk is cut out around these fingers so as to permit said fingers to readily yield. It will be noted that the cap member 23 fits comparatively snug within the box 14, but has the major portion of its periphery bevelled so as to reduce frictional contact with the circular wall of the box. By reason of the spring fingers 29 the cap member 23 may move longitudinally of the box when displaced by a longitudinal movement of the staff, thus yielding to an end thrust when said cap member is not designed to undergo lateral displacement.

One of the very important features of the invention is the intermeshing relation between the jewel-mounting members 20 and 23.

23. The member 20 is somewhat less in diameter than the member 23 so as to be free to undergo a lateral movement. The member 20 has a V-shaped groove 30 and the member 23 has a V-shaped annular bead or boss 31 conforming to and fitting into said groove so that the adjacent surfaces of the mounting members may contact if desired. The fingers 29 hold the member 23 in contact with the member 20 and the latter in contact with the inner side of the plate 14, whereby both members are resiliently sustained by a single spring device or element.

It will be apparent that a side thrust of the member 20 will cause the inclined walls of the groove 30 to ride along the inclined walls of the boss 31, thus displacing the member 23 longitudinally with relation to the staff 12 and the member 20 laterally with relation to the staff, as is indicated in Fig. 5. Such a movement of the two members permits the balance staff to move longitudinally at the same time it is moving laterally and its movement thus becomes universal, whereby any thrust is resiliently taken up and the staff is cushioned as the result of a sudden shock or jar, thereby being saved from rupture, injury or breaking.

The single spring element and the intermeshing engagement of the mounting members is practical and simple and reduces to a minimum the number of parts employed, as well as making for substantiability and easy assembly. The other box 14 which is inserted in the recess 13 of the plate 10 has the same thrust absorbing members, but the collar 18 is omitted from the plate 15 and the plate 15 is not countersunk, as is the case where it is mounted in the bracket 11. However, the plate 15 of the other box forms a bumper for the small roller 32 which is on the staff 12 and thus limits the end thrust of the staff. It will be seen that the boxes 14 and the spring disks 26 can be readily applied to the plate and bracket of a watch movement without an expensive operation and may be easily removed when necessary.

The jewel member 20 may be referred to as the inner jewel-mounting member, while the member 23 may be referred to as the cap jewel-mounting member.

Various changes in the size and shape of the different parts, as well as modifications and alterations, may be made within the scope of the appended claims.

What I claim, is:

1. In a pivot bearing device for a watch balance staff, an inner jewel-mounting member mounted to bodily move laterally, a cap jewel-mounting member intermeshing with the adjacent face of the inner member and normally holding the inner member in position and against lateral movement relatively thereof, and resilient means acting axially of the staff for engaging the cap jewel-mounting with the inner mounting and constituting the sole resilient sustaining means for both members.

2. In a pivot bearing device for a watch balance staff, a jewel box having a central opening for receiving a balance staff and a bumper surrounding said opening for limiting the end thrust of the balance staff, an inner jewel-mounting member carrying a perforated jewel and disposed within said box for lateral movement, a cap jewel-mounting member carrying a cap jewel and mounted in said box for longitudinal movement and restrained against lateral movement, the cap jewel member having sliding intermeshing engagement with the inner member whereby the outer member is displaced longitudinally by a lateral movement of the inner member, and a spring member acting axially of the staff for engaging the cap member for yieldably sustaining both of the jewel mounting members in contact.

3. In a pivot bearing device for a watch balance staff, an inner jewel-mounting member having a perforated jewel and provided with a V-shaped groove, a cap jewel-mounting member provided with a cap jewel and having a V-shaped boss engaging in the groove of the inner member, and a spring disk having fingers tensioning the cap member into interlocked engagement with the inner member.

4. In a pivot bearing device for a watch balance staff, an inner jewel-mounting member mounted for free lateral movement, a cap jewel-mounting member intermeshing with the inner member and retained against lateral movement but movable upon the inner member longitudinally of the staff, and means for yieldingly retaining the cap member in contact with the inner member to effect opposite movements of said members by pressure transmitted from one to the other.

In testimony whereof I affix my signature,
LOUGH P. SIGLER.
